UNITED STATES PATENT OFFICE.

WILBUR H. RADFORD, OF ATHENS, OHIO.

BOOK.

1,091,162.

Specification of Letters Patent. Patented Mar. 24, 1914.

Application filed March 7, 1913. Serial No. 752,697.

To all whom it may concern:

Be it known that I, WILBUR H. RADFORD, a citizen of the United States, residing at Athens, in the county of Athens and State 5 of Ohio, have invented a new and useful Book, of which the following is a specification.

One object of the present invention is to provide a book which may be bound at a 10 minimum expense and with a minimum expenditure of labor.

Another object of the invention is to provide novel means for assembling the backing strips with the back of the book.

Another object of the invention is to provide a book in which the ends of the securing elements are concealed and hidden by the hinge strips of the covers.

The invention aims to improve generally 20 and to increase the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of invention herein disclosed can be made within 30 the scope of what is claimed without departing from the spirit of the invention.

In the drawing:—Figure 1 shows the book in perspective, the parts thereof being separated; Fig. 2 shows the book in assembled form; Fig. 3 is a side elevation showing the book partially open; Fig. 4 is a plan of one of the washers; and Fig. 5 is a transverse section of the back of the book.

The covers of the book are denoted by the numeral 1 and are provided with hinge strips 2 which preferably are fashioned from cloth, although any other flexible material may be employed. The hinge strips 2 are 40 bent upon themselves, to form tongues 3 which may be reinforced along their longitudinal edges as shown at 4. Securing elements 5 which may be rods or spikes extend upwardly through the reinforced portion 4 of the tongue 3 of the lower cover 1, as shown in Fig. 3, the heads of the securing elements 5 being concealed by the lower cover. Backing strips 6 are provided, the strips 6 being made of cloth, or the like. 50 The strips 6 are bent upon themselves along

their inner longitudinal edges as shown at 7, to form a reinforcement. The leaves 8 are located between the edges 7 of the backing strips 6, and the securing elements 5 pass through said reinforced portions 7 and 60 through the leaves 8, the leaves 8 being perforated to receive the securing elements 5. Presupposing that the book is in the position shown in Fig. 3, the upper ends of the securing elements pass through the reinforced portion 4 of the hinge strip 2 of the upper 65 cover and washers 9 are placed around the upper ends of the securing elements 5, the washers 9 resting upon the reinforced portion 4 of the hinged strip 2 of the upper 70 cover. The washers 9 are each provided with a central hole 10 adapted to receive one of the securing elements 5 and from the hole 10 radiate ribs 11 which serve to stiffen the washers. The upper ends of the securing elements 5 are turned over or butt-ended 75 upon the washers 9 and when the upper cover is swung from the opened position shown in Fig. 3 to the closed position shown in Fig. 2, the washers 9 and the securing 80 elements, at their upper ends, will be concealed.

The back of the book which is indicated at 12, may be made of wood, cardboard, or other like material. The back 12 may be 85 surrounded by a covering 14 of cloth or the like. The backing strips 6 are overlapped upon each other as shown at 15 and are glued to the covering 14 and to the back 12, the ends of the backing strips 6 being extended 90 around the ends of the back 12 as shown at 16.

From the foregoing it will be seen that there is presented in this application, a book which may be bound readily, with a minimum expense both as to labor and to material.

Having thus described the invention what is claimed is:—

1. A book comprising a back; a flexible 100 backing structure secured in its intermediate portion to the back and having its edges extended beyond the back; leaves located between the edges of the backing structure; a securing element passing through the 105 leaves and engaging the edges of the backing structure; and a cover connected with the securing element.

2. A book comprising backing strips; leaves located between the edges of the back- 110

ing strips; a back, the backing strips being overlapped upon, and secured to, the back; and securing elements passing through the edge of the backing strips and through the leaves.

3. A book comprising hinge strips; backing strips located between the hinge strips; leaves located between the edges of the backing strips; securing elements passing through the hinge strips, the edges of the backing strips and the leaves, the hinge strips being bent to overhang the ends of the securing elements; covers assembled with the hinge strips; and a back, the backing strips being overlapped and secured to the back.

4. A book comprising backing strips; a leaf located between the edges of the backing strips; a back, the backing strips being overlapped upon, and secured to, the back; and a securing element passing through the

edges of the backing strips and through the leaf.

5. A book comprising hinge strips; backing strips located between the hinge strips; a leaf located between the edges of the backing strips; a securing element passing through the hinge strips, the edges of the backing strips and the leaf, the hinge strips being bent to overhang the ends of the securing element; covers assembled with the hinge strips; and a back, the backing strips being overlapped upon and secured to the back.

In testimony that I claim the foregoing as my own, I have hereto affixed my signature in the presence of two witnesses.

WILBUR H. RADFORD.
